UNITED STATES PATENT OFFICE.

JESSE W. RENO, OF NEW YORK, N. Y.

TUNNEL CONSTRUCTION.

SPECIFICATION forming part of Letters Patent No. 754,807, dated March 15, 1904.

Application filed November 9, 1903. Serial No. 180,350. (No model.)

To all whom it may concern:

Be it known that I, JESSE WILFORD RENO, a citizen of the United States of America, and a resident of the city, county, and State of New York, have invented certain new and useful Improvements in Tunnel Construction, of which the following is a specification.

My invention relates to the construction of tunnels, and has for its object to provide a method and a construction for tunnels especially adapted for the easily-compressible earth—such as silt, wet sand, and the like—frequently found under the beds of rivers.

My invention consists in providing a tunnel-shell preferably of the well-known type in which segmental iron rings are bolted together to form a tunnel-wall, in providing straight wooden piles beneath the base of said tunnel, in providing interlocked transverse concrete blocks resting upon said piles and secured to the tunnel-shell, in providing beams embedded in said blocks, so as to break joints therewith, and in other novel features of the construction.

My invention consists, further, in providing a mechanical process or method by means of which my construction may be practically carried out.

The method of constructing a tunnel of segmental cast-iron rings is well known and consists, essentially, in driving a circular cutting-shield into the earth by hydraulic or other means, in excavating the material within the shield, and in placing circular segmental rings behind the shield as it is forced forward. A partition or bulkhead is placed in the completed tunnel a short distance behind the cutting-shield, and in the compartment thus formed air is maintained at a pressure sufficient to keep the water from entering this working compartment. Material is taken in and out of the working compartment through a suitable air-lock in a manner which is well understood. Tunnels of this description are well adapted for certain situations, especially when they are not of great size and where the ground is comparatively hard or compact and where the traffic through the tunnel is not heavy. My present construction, however, is designed for places where the earth through which the tunnel passes is comparatively soft and yield-

ing, where the tunnels are large enough to take in the standard cars and locomotives of the steam-roads, and where the speed of trains will be very high. Under these conditions the thin shell of the ordinary tunnel construction is not rigid enough to withstand the enormous concentrated weights moving rapidly over it. Moreover, the vibrations caused by the rapidly-moving trains set up a motion in the particles of earth which immediately surround the walls of the tunnel, causing an unstable support for the walls and resulting in cracks and leaks in the tunnel.

In Patent No. 723,307, issued to me March 24, 1903, I describe a method of tunnel construction especially adapted for certain conditions of soft and easily-compressible earth in which the tunnel-shell was reinforced by a massive concrete girder joined to its base.

In my present invention I also employ a massive concrete girder joined to the base of the tunnel, but constructed in a different manner and by a different method, and I employ in addition a foundation of piles, preferably the ordinary wooden piles, for the concrete girder to rest upon, and I provide a novel method for driving the piles in place from within the tunnel. These piles may be made of sufficient number and length to be able to alone sustain the entire live loads passing through the tunnel.

I will first describe the tunnel structure and afterward the method and process employed in its construction.

In the drawings accompanying and forming part of this specification, Figure 1 represents a longitudinal section through the center of the tunnel, showing at different points the different stages of construction. Fig. 2 is a transverse section on line *a a* of Fig. 1. Fig. 3 is a partial horizontal section on line *b b* of Fig. 1 through the hydraulic pile-driver. Fig. 4 is a detailed view of the beveled plates. Fig. 5 is a partial transverse section of the completed tunnel. Fig. 6 is a partial longitudinal section of the lower portion of the tunnel, showing a modified form. Fig. 7 is a partial transverse section of the construction shown in Fig. 6. Fig. 8 is an enlarged plan view of the special segments in the construc-

tion shown in Figs. 6 and 7, and Fig. 9 is a transverse section on line *c c* of Fig. 8.

The reference characters are used in the same sense in all of the drawings and the specification.

Numeral 1 represents the segments, usually made of cast-iron, of which the main portion of the tunnel-shell is composed. These segments are bolted together in the usual manner and when completed are lined with a wall of concrete, which is not shown in the drawings, as it forms no part of my present invention. The two lower rows of segments are in the preferred form of my present invention removed, and the springing-segments 2 of the arch thus formed are anchored or secured by the bolts 3 to the concrete base 4, as shown in Fig. 5. The concrete base 4 is made up of transverse blocks 5 of a length and width substantially equal to the length and width, respectively, of the opening formed by the removal of four segments. These blocks are interlocked by means of the recesses 6 and tongue 7, and they are also tied or bound together by means of the I-beams 8, which are of a length substantially equal to the width of the concrete blocks and are embedded half-way in one and half-way in the other, so that the joint between adjacent concrete blocks 30 comes substantially in the middle of the beams embedded in those blocks. Before these blocks are formed wooden piles of a length substantially equal to the diameter of the tunnel are driven down into the earth, so that 35 when the blocks are afterward formed they rest upon and embed the tops of the piles. These transverse concrete blocks, with the beams which are embedded in them and tie them together, form a practically continuous 40 concrete bed or girder, which rests upon a number of piles capable of sustaining the entire live load of the tunnel, and they form an efficient load-distributing member, whereby a concentrated load is distributed over a relatively great length.

In the modified form of my invention shown in Figs. 6, 7, 8, and 9 special floor-segments are provided. The centers of these segments are provided with openings 10, which are temporarily closed by the caps 11. These segments have peripheral flanges 12, corresponding to the flanges of the regular segments, and these segments are provided with the usual bolts 13, and the caps are provided with notches 14, which register with the heads and nuts of the bolts to permit the caps to be withdrawn without removing the bolts, the caps being held in place temporarily by means of the blocks or wedges 15. In the completed tunnel, the caps 11 having been previously removed, the flanges 12 are embedded in the concrete base 4. It will be seen that by means of this construction a continuous concrete girder is provided, which is securely anchored or bound to the tunnel-shell and is continuously

supported upon the tops of piles embedded in the lower surface of the concrete.

I will now describe the method by which my improved tunnel is constructed.

The tunnel is driven from a heading by means of a circular shield by the well-known method. The special floor-segments illustrated in Fig. 1 are provided with beveled faces 16, which when bolted together form a recess for the reception of the beveled plate 17. The beveled plates 17 are provided with elongated slots 18 for the reception of a key 19. When the heading has been carried forward a convenient distance, the keys 19 are driven in the elongated slots in a beveled plate, 75 and the beveled plate thus forced out from between the two segments. By this means the segments are freed and may be easily withdrawn. Four segments are preferably removed in this manner, leaving an oblong opening in the base of the tunnel. Metallic sheeting 20 is then driven down into the earth at the sides and ends of the opening along the front side of the opening, and preferably wooden sheeting 21 is driven at the sides of 80 the opening, the sheeting 21 at the sides being left in place, while sheeting 20 will be withdrawn after the concrete has been fixed in place and the following four segments have been removed. After the sheeting has been 95 properly driven the earth is excavated to the depth required for the concrete, and wooden piles, preferably eight in number and placed as indicated in the drawings, are driven in a manner which will be hereinafter described. 100

Forms consisting of the transverse pieces 22 and the longitudinal pieces 23 are secured in place, as shown, for the purpose of holding the sheeting in position, the transverse pieces 22 also serving the purpose of forming the 105 recess or groove 6 in the concrete block which is to receive the tongue 7 of the following block. The sheeting 20 is preferably made of strips of metal plate, and certain of these strips, as 25 and 26, have formed in their adjacent edges recesses, through which the I-beams 8 may be forced. After the sheeting has been driven in place and the excavation made, and preferably after the piles are driven, the short sections of I-beams 8 are forced for 110 half of their lengths through the openings in the sheeting strips 25 and 26 into the earth under the segments in front of the excavation, as is indicated in Fig. 5, and, as will be obvious, it will be necessary to stagger the consecutive sections of I-beams to avoid interference while they are being forced in place. When the excavation has been made, the piles driven, and the I-beams forced in position, the transverse form 22 in the preceding concrete block 5 is withdrawn from said block, the other forms 22 and 23 being allowed to 115 remain in position, and the concrete is then tamped in the excavation and may be brought up to the desired height in the tunnel. 120

In order to force piles of a length substantially equal to the diameter of the tunnel, I provide a hydraulic cylinder of a diameter somewhat greater than that of the piles to be driven, so that the piles may be received into said cylinder, and I provide a hydraulic piston adapted to operate in said cylinder and means for pivoting the cylinder, preferably so that it may be tilted in any direction. I also provide means for conveniently moving the hydraulic cylinder backward and forward in the tunnel and means for conveying material to and from the heading in such a manner that the work in the heading and the carrying of material back and forth may be carried on simultaneously and without interference with the operations of forming the concrete beds or driving the piles therefor. This provision of a method by means of which two sets of operations may be carried on simultaneously and without interference with each other is of the very greatest practical and economical importance.

Two platforms 27 are arranged longitudinally of the tunnel at substantially the level of the center of the tunnel along the sides, leaving an open space 28 between. These platforms are supported upon vertical posts 29 and horizontal sills 30. Upon these platforms are arranged tracks 31, adapted to support trucks of ordinary construction for the transportation of material in and out of the tunnel, and upon the inner edges of the platforms rails 32 are provided for supporting the truck which carries the hydraulic cylinder 33.

The truck may be constructed in any convenient manner which will permit the proper movements of the hydraulic cylinder. As shown in the drawings, it consists of the wheels 34, the rear axle 35, and the front axle 36, which is arched upward, as shown, to permit the hydraulic cylinder to swing to a horizontal position for the reception of a pile. Mounted on the front and rear axles are longitudinal members 37, preferably mounted so that they may slide transversely of the truck, and mounted upon these longitudinal members in the bearings 38 is the gimbal-joint 39, having the outer ring 40 and the inner ring 41, to which latter the hydraulic tube is rigidly secured. The shaft 41 of the gimbal-joint is provided at its outer end with the worm-gear segment 42, which is actuated by the worm 43 and hand-wheel 44. Secured to the upper end of the hydraulic tube is the frame 45, which is preferably made to clear by a small space the segmental ring of the tunnel-shell. Blocks 46 are provided to be inserted between the tunnel-shell and the form 45, so that the tunnel-shell may receive the thrust due to the hydraulic pressure within the cylinder. A pipe 47 is connected with the end of the cylinder and with any convenient source of water under pressure.

When a pile is to be driven, the hydraulic cylinder is brought to a substantially-horizontal position and the pile placed in it. The pile and cylinder are then brought to a vertical position over the point where the pile is to be driven. The blocks are then inserted between the frame 45 and the tunnel-shell, and hydraulic pressure is applied to the cylinder and the piles forced into the earth. When the upper end of the pile has been forced down below the lower end of the cylinder, a short piece of pile may be inserted in the cylinder, which will then be brought again in position over the pile and the pile forced down the remainder of the way to the proper depth, or this last stage of driving the pile may be accomplished by means of any approved form of pile-driver, as by a falling weight, as there is then a sufficient working space above the top of the pile for this purpose.

Having thus described my invention, what I claim is—

1. In a tunnel construction, the combination with a cylindrical shell of a series of transverse concrete blocks joined to the base of said shell.
2. In a tunnel construction, the combination with an arched tunnel-wall, of transverse blocks joined to its springers.
3. In a tunnel construction, the combination with an arched tunnel-wall, of interlocking transverse blocks joined to its springers.
4. In a tunnel construction, the combination with an arched tunnel-wall, of transverse blocks joined to its springers, and longitudinal beams embedded in said blocks, each beam extending through a plurality of blocks.
5. In a tunnel construction, the combination with a segmental shell, of a continuous concrete bed joined to the base of said shell formed of transverse blocks, having embedded therein longitudinal girders adapted to break joints between said blocks and piles driven beneath said concrete bed and having their tops engaging the same.
6. The method of tunnel construction consisting in forming a segmental tunnel-shell, removing floor-segments in the base of said tunnel-shell, driving piles from within the tunnel through the openings formed, and securing the tops of said piles to said tunnel-shell.
7. The herein-described method of constructing tunnels which consists in forming a segmental tunnel-shell, removing floor-segments, driving straight piles through the openings made by the removal of said floor-segments from within the tunnel, forming a concrete bed upon the tops of said piles, and securing said bed to the tunnel-shell.
8. The herein-described method of constructing tunnels which consists in forming a segmental tunnel-shell, removing floor-segments, driving piles through the openings

thus formed, forming a load-distributing member upon the tops of said piles and securing said load-distributing member to said tunnel-shell.

5 9. The herein-described method of tunnel construction which consists in forming a segmental tunnel-shell, removing floor-segments, providing a hydraulic cylinder adapted to receive a pile, placing a pile in the hydraulic cylinder and applying hydraulic pressure to force said pile down through the openings in the floor of said tunnel.

10 10. The herein-described method of constructing a reinforced tunnel which consists in 15 constructing a segmental tunnel-shell, forming temporary openings in the floor of said segmental tunnel-shell, mounting a hydraulic cylinder adapted to receive a pile within said tunnel-shell, placing a pile in said cylinder 20 and providing hydraulic means for driving piles from said hydraulic cylinder through the openings in the base of said tunnel-shell.

11 11. The herein-described method of constructing a reinforced tunnel which consists in 25 forming a segmental tunnel-shell, removing segments in the base of said tunnel-shell, providing a tramway within said tunnel and mounting thereon a hydraulic cylinder adapted to receive piles, placing piles in said cylinder 30 under, forcing said piles from said hydraulic cylinder through the base of said tunnel, form-

ing a concrete bed upon the tops of said piles and securing said bed to said tunnel-shell.

12. The herein-described method of constructing tunnels which consists in forming a 35 segmental tunnel-shell, removing segments from the floor of said shell, excavating a trench therebeneath, forcing piles down through the openings formed in the bottom of the tunnel-shell, filling said trench with 40 concrete and securing said concrete to said tunnel-shell.

13. In a tunnel construction, the combination of metallic segments provided with transverse beveled faces, with beveled plates adapted to be received between said beveled faces, and means for withdrawing said beveled plates to loosen said segments. 45

14. In a tunnel construction, the combination with a cylindrical segmental tunnel-shell, 50 of platforms arranged along the sides and at substantially the height of the center of said tunnel-shell, leaving an opening therebetween; and tracks laid upon said platforms.

In testimony whereof I have signed my name 55 to this specification in the presence of two subscribing witnesses.

JESSE W. RENO.
